CLAIM

The ornamental design for a shower scrubber, as shown and described.

DESCRIPTION

FIG. 1 is a perspective view of a shower scrubber with the broken line showing of a scrubber insert being for illustrative purposes only and forming no part of the claimed design;

FIG. 2 is a front elevation view thereof;

FIG. 3 is a right side elevation view thereof, the left side being a mirror image;

FIG. 4 is a top plan view thereof, the bottom view being a mirror image; and,

FIG. 5 is a rear elevation view thereof.

1 Claim, 1 Drawing Sheet Fig. 1.

Fig. 2.

Fig. 4.

Fig. 3.
